UNITED STATES PATENT OFFICE

OSCAR M. ANDERSON, OF NEW BRITAIN, CONNECTICUT, ASSIGNOR TO LANDERS, FRARY & CLARK, OF NEW BRITAIN, CONNECTICUT, A CORPORATION OF CONNECTICUT

DESIGN FOR AN ELECTRIC VACUUM CLEANER

Application filed March 22, 1933. Serial No. 47,547. Term of patent 14 years.

To all whom it may concern:

Be it known that I, OSCAR M. ANDERSON, a subject of the King of Sweden, and a resident of New Britain, in the county of Hartford, State of Connecticut, have invented a new, original, and ornamental Design for an Electric Vacuum Cleaner, of which the following is a specification, reference being had to the accompanying drawing, forming part thereof.

Fig. 1 is a front elevational view of an electric vacuum cleaner showing my new design; and

Fig. 2 is a perspective view thereof.

I claim:

The ornamental design for an electric vacuum cleaner as shown.

OSCAR M. ANDERSON.
